COMBINED CLOCK AND RADIO

Robert L. Sampson, 2244 S. Western Ave., Chicago, Ill.

Filed May 5, 1961, Ser. No. 65,036

Term of patent 14 years

(Cl. D56—4)

Fig. 1

Fig. 2

Fig. 3.

Fig. 4

Fig. 5.

FIG. 1 is a front elevational view of a combined clock and radio showing my new design;

FIG. 2 is a side elevational view;

FIG. 3 is a top plan view;

FIG. 4 is a rear perspective view thereof; and

FIG. 5 is an enlarged fragmentary view of a portion of the lower right hand corner of FIG. 1.

I claim:

The ornamental design for a combined clock and radio, as shown.
